UNITED STATES PATENT OFFICE.

GORDON E. McLENDON, OF MEMPHIS, TENNESSEE.

COMBINED IRONING-BOARD AND STEP-LADDER.

1,130,417.

Specification of Letters Patent. Patented Mar. 2, 1915.

Application filed July 22, 1913. Serial No. 780,501.

To all whom it may concern:

Be it known that I, GORDON E. McLENDON, a citizen of the United States, residing at Memphis, in the county of Shelby and 5 State of Tennessee, have invented certain new and useful Improvements in Combined Ironing-Boards and Step-Ladders, of which the following is a specification.

This invention relates to improvements in 10 an article of household utility and has for its object to provide a combined ironing board and step ladder.

Another object of the invention is to provide an ironing board having a support 15 therefore and being so constructed that it is equally adapted to be used as a step ladder.

With the above and other objects in view I have invented the device illustrated in the accompanying drawings, in which—

20 Figure 1 is an elevational view of my device set up as an ironing board, Fig. 2 is an elevational view of the device folded, Fig. 3 is a front elevational view of the device as used for a step ladder and Fig. 4 is a side 25 elevational view of Fig. 3.

Like reference characters indicate like parts throughout the specification and in the several views in the drawings in which—

1 indicates an ironing board having the 30 upper step 2 of a step ladder 3 hingedly secured to its small end 4. To the central portion of the standards 5 and 6 of said ladder is secured a two section brace member 7 the sections 8 and 9 of which are held together 35 by means of a rule hinge construction 10 so that when the device is used as an ironing board, the opposing inner ends 11 and 12 of said sections abut against one another and are thereby held rigid when the round 40 13 is caught in either of the brackets 14, 15 or 16, the standards 5 and 6, and the member 7 forming a stand or support for the board. 1. By means of the brackets 14, 15 and 16, which are spaced apart to suit, the ironing 45 board may be set at any desired height.

When the device is used as a ladder the large end 17 of the board 1, together with the lower and free ends 18 and 19 of the ladder are set upon the floor and spaced apart 50 from one another until the round 13 can be

seated in (preferably) the bracket 15, whereby the members 1 and 3 are held rigidly together, the member 9 swinging down against the lower part of the ladder 3, and out of the way. Steps 20 are provided between the standards 5 and 6 whereby the ladder is formed. 55

When it is desired to compactly fold the device the member 8 is thrown upwardly between the members 1 and 3, when the ladder 60 may be swung up closely against the ironing board, as shown in Fig. 2 of the drawings. The edge 21 of the portion 17 is formed straight so as to firmly support the ladder. 65

Having now described my invention, that 65 which I claim to be new and original and desire to procure by Letters Patent is:

1. In combination an elongated base-board, two elongated legs hingedly connected to one end of the base board, braces connecting said legs together, a pair of sectional legs pivotally connected to the sides of said elongated legs, the members of said sectional legs having a butt joint, and stops carried by said base-board against which 70 the ends of said sectional legs may abut whereby to cause the legs to intersect to horizontally support said base-board. 75

2. In combination, a table-board, a stepped elongated frame hingedly connected 80 to one end of said table-board, oppositely-arranged two-section legs pivotally connected to the sides of said frame, said two sections, when extended, arranged to have a butt joint, said sections when extended and adjoined arranged to intersect said frame, stops carried by said table-board engaged by certain of said sections whereby to hold said sections in alinement, stops carried by said table-board in advance of said other 85 props engaged by certain of said sections, whereby to hold said frame in an angular position relatively to said table-board. 90

In testimony whereof I affix my signature in presence of two witnesses.

GORDON E. McLENDON.

Witnesses:

A. B. FALLS,
J. H. SCHWINN.
